UNITED STATES PATENT OFFICE.

GEORGE C. YOCUM, OF SCRANTON, PENNSYLVANIA.

VENDING-MACHINE.

No. 841,210

Specification of Letters Patent.

Patented Jan. 15, 1907.

Application filed January 15, 1906. Serial No. 296,110.

To all whom it may concern:

Be it known that I, GEORGE C. YOCUM, a citizen of the United States, residing at Scranton, in the county of Lackawanna and State of Pennsylvania, have invented certain new and useful Improvements in Vending-Machines, of which the following is a specification.

My invention comprises a motor-driven vending-machine in which the motor which actuates the delivery mechanism may be operated to deliver one or more articles, depending upon the value of the coin inserted in the machine.

In the accompanying drawings I have illustrated my invention in connection with a machine for feeding and cutting off tickets from a ticket-strip, the machine there shown being designed particularly for vending soda-water and other checks or tickets which are to be exchanged by the purchasers for drinks.

The construction, operation, and advantages of my improved vending mechanism will be clear from the following specification, taken in connection with the accompanying drawings, in which—

Figure 1 is a top plan view of the machine, the back of the casing being removed and the cover being shown in horizontal section on a line passing through the openings in the cover for the delivery of tickets and ejected coins, the movable parts of the mechanism being shown in their normal positions. Fig. 2 is a vertical section through the machine on the line 2 2 of Fig. 1, showing the coin-operating mechanism in side elevation, the coin-balance and coin-releasing parts being shown in their normal positions and the main operating-gear of the motor being omitted. Fig. 3 is a detail view looking from the rear of the machine, showing the fan-governor and the movable detent for stopping and releasing the motor. Fig. 4 is a right side view of the coin-balance and the mechanism for releasing the coins, the releasing devices being shown in their normal positions and the coin-balance being shown in full lines in the position which it occupies when a dime is first inserted into the balance, the dotted lines indicating the position of the balance after the coin has been released from the first pocket or compartment of the balance and has moved into the second pocket or compartment. Fig. 5 is a left side view of the coin balance and releasing mechanism, the parts being shown in the positions which they occupy at

the time when the coin is released from the first compartment of the balance. Fig. 6 is a top plan view of the coin balance and releasing devices, the parts being shown in the same positions as in Fig. 5. Fig. 7 is a front view of the coin-chutes and coin-balance, one of the chutes being partly broken away, and Fig. 8 is a diagrammatic view illustrating the manner in which a coin is ejected from the machine if inserted into the coin-chute while the motor is in operation.

Referring to Figs. 1 and 2 of the drawings, A indicates a suitable casing within which the vending mechanism is contained. Within the base of the casing is a removable cash-drawer B, above which is suitably arranged a base C, which supports the movable parts of the vending mechanism. On this base between a pair of horizontal plates 1 and 2 is arranged a suitable spring-motor D, which may be wound up by means of a key applied to the winding-shaft 3 at the center of the main operating-gear 4.

It is unnecessary to describe or illustrate the motor and the ticket-feeding and cutting-off mechanism in detail, since the specific form of motor and the delivery mechanism are not claimed herein. It may be stated briefly, however, that the main operating-gear 4 drives a shaft on which is mounted a bevel-pinion 5, the latter meshing with a pinion 6 upon a shaft 7, carrying a rotary knife 8, which knife is adapted to cut off a ticket from a ticket-strip 9 after the feed-wheels 10 have fed the strip forward the length of one ticket. These feed-wheels are intermittently operated to feed the strip forward through an opening 11 in the casing by means of a clutch 12, having a crank-arm 13, connected by a link 14 to a lever 15, the latter being connected at one end by a pivot-pin 16, Fig. 6, to the top plate 1 of the motor and being connected at a point intermediate of its ends by a link 17 to a rotatable arm or lever 18. This lever 18 is connected at one end to a shaft 19, having thereon a pinion 20, which meshes with the operating-gear 4. It will be readily seen the arrangement is such that for each rotation of the shaft 19 the lever 15 and crank 13 will be moved backward and forward, thus causing the feed-wheels to move the ticket-strip intermittently. After the feed movement of the strip has ceased the knife 8 severs the strip.

If a coin of the value of one ticket is in

serted in the machine, but one ticket will be fed forward and cut off; but if a coin having the value of two tickets is inserted by design or accident the machine will feed and cut off tickets. This is accomplished by the mechanism which will now be described. Upon a suitable standard 21, projecting upwardly from the top plate 1 of the motor, is pivoted a coin-balance E, consisting of a lever 22, having on its shorter arm a weight 23 and upon its longer arm a coin-receptacle comprising the two plates 25 and 26, secured to the sides of the lever 22 and projecting upwardly therefrom; these sides flaring outwardly at the top, as shown in Figs. 1, 2, 6, and 7. This coin-receptacle has a primary compartment e adjacent to the pivotal point 27 of the lever and a secondary compartment e' at the outer end of the lever. A coin-retaining device e² is arranged at the outer end of the primary compartment e, and a coin-retaining device e³ is arranged at the outer end of the compartment e', these retaining devices being normally in positions to prevent coins from rolling out of the compartments.

As shown in Figs. 4 and 6, the coin-retaining device e² consists of a wire having a central portion journaled in a bearing 28, arranged longitudinally of the coin-receptacle, said wire having an upwardly-turned portion 29, provided with an overturned end 29^a, which normally extends through slots 30 in the sides 25 and 26 and is adapted to prevent coins inserted in the compartment or pocket e from passing into the compartment or pocket e'. The coin-retainer e² also has an arm 29^b, which extends downwardly and thence laterally beneath the coin-receptacle, as shown in Figs. 4 to 7, inclusive. The coin-retainer e³, as shown, also consists of a wire having its central portion pivoted in a suitable bearing 31, arranged on the under side of the lever 22, and this wire has an upwardly-projecting portion 32 with an overturned end 32^a at the outer end of the compartment e' to engage and prevent coins from rolling out of said compartment. The opposite end portion 32^b of the wire extends downwardly and thence laterally in the same general direction as the arm 29^b of the coin-retainer e², as shown best in Fig. 7. When the coin-balance is in its normal or horizontal position, as shown in Figs. 2 and 7, these arms 29^b and 32^b of the coin-retainers extend over the arms 33 and 34, respectively, of a tripping-lever F; but in the normal position of the coin-balance these arms of the coin-retainers do not engage the arms of the tripping-lever.

The coin-balance is normally held in the horizontal position (shown in Fig. 2) by the weight 23, and in this position of the coin-balance the motor is stopped or locked against movement by a detent-lever 35, Figs.

3, 4, and 5, one end of which is connected to the shorter arm of the coin-balance by a link 36. The opposite end of the detent-lever normally engages a pin 37, upon the shaft of a fan-governor 38, which is suitably driven by a train of gearing G from the motor. When the coin-balance is tilted, however, as shown in Figs. 4 and 5, the detent-lever is moved into the dotted position shown in Fig. 3, thus releasing the motor, as will be evident. When the coin-balance returns to normal position, the detent 35 moves into the path of the stop-pin 37 and stops the motor.

Coins of different denominations, such as dimes and five-cent pieces, are delivered from the coin-chutes X and V into the pockets or compartments e and e' of the coin-balance, as will be hereinafter described. When a dime enters the compartment e, it causes the coin-balance to tilt into the position shown in full lines in Fig. 4, thus moving the detent-lever 35 out of engagement with the stop-pin 37 and releasing the motor. In this position of the coin-balance the arm 29^b of the coin-retainer e² rests upon the upper arm 33 of the forked releasing-lever F; but the arm 32^b of the coin-retainer e³ is some distance above the lower arm 34 of the forked lever, as shown in Fig. 4. In this position a short upward movement of the forked lever will rock the retainer e² without rocking the retainer e³. When the motor starts, the lever 18 rotates from its normal position (shown in Fig. 1) in the direction of the arrow and causes the movement of the feed-wheels. The knife 8 is simultaneously rotated by the motor, and a ticket is fed and cut off by the time the lever has made one complete revolution. As the lever 18 nears the end of a revolution a cam 18^a on the end of the lever passes under the lower arm 34 of the forked lever F and raises the latter lever, thus locking the coin-retainer e² until its overturned end 29^a is moved out of the path of the coin, as shown in Fig. 6. The dime d then runs into the secondary compartment e' of the coin-receptacle and is prevented from leaving the coin-balance by the secondary retainer e³. After the coin-retainer e² has been moved to release the coin, the rotary lever 18 passes out under the forked lever F, allowing the latter to return to the position shown in Fig. 4, wherein the free end of the arm 34 rests upon the top plate 1 of the motor. When the dime reaches the secondary pocket e' and the forked lever F drops to its normal position, the longer arm of the coin-balance tilts farther downward, as indicated in dotted lines in Fig. 4, (owing to the shifting of the weight of the coin to the outer end of the balance,) and the arm 32^b of the coin-retainer e³ swings backward, as indicated in dotted lines in said figure, over the portion 34^a of the arm 34, which is higher

than the outer portion 34^b of said arm. The motor continues in operation while the lever 18 is making a second revolution and a second ticket is fed and cut off. As the rotary lever 18 nears the completion of its second revolution the cam 18^a at its free end passes under the arm 34 of the forked lever F as before and lifts the latter lever. When the lever F lifts, the coin-retainer e³ is rocked thereby until its overturned end 32^a is moved out of the path of the coin, and the latter then rolls off of the end of the balance and into a chute 39, through which it is conducted into the cash-drawer B. During this second upward movement of the forked lever the coin-retainer e³ is also rocked, although no function is then performed by this retainer. After the coin leaves the coin-balance the latter swings back into its horizontal position, and the detent 35 is thereby moved into position to engage the stop-pin 37 and stop the motor. The lever 18, however, passes from under the forked lever F before the motor is stopped by the return movement of the coin-balance.

It will thus be seen that a dime inserted in the primary pocket or compartment e of the coin-balance will cause two tickets to be delivered. When a "nickel" or five-cent piece is inserted in the machine, it enters the secondary pocket e' on the outer end of the coin-balance, and the latter immediately swings into the dotted position shown in Fig. 4, or slightly below said dotted position, so that on the first ensuing revolution of the rotary lever 18 the raised portion 34^a of the forked lever F will engage and move the coin-retainer e³. The five-cent piece will therefore drop off of the coin-balance into the chute 39 near the end of the first revolution of the lever 18, and but one ticket will be delivered before the motor is stopped by the return of the coin-balance to its normal position.

In order to regulate the movement of the coin-balance, a counterbalance-weight 40 is arranged so as to increase the weight applied to the shorter arm of the balance when a coin enters the secondary pocket. As shown, this weight is suspended upon a wire rod 41, which is pivotally mounted in the standard 21 above the pivotal point of the coin-balance. This wire rod, as shown in Fig. 6, has a horizontal portion 41^a, which passes through suitable openings or bearings in the yoke of the standard 21, and the end 41^b of the arm extends over the weight 23. In the normal position of the coin-balance the end 41^b of the wire is above and out of engagement with the weight 23, as shown in Fig. 2, so that the coin-balance is easily tilted by a dime entering the primary pocket. When the dime moves into the secondary pocket or a nickel enters said pocket, the weight 23 presses upwardly against the end 41^b of the

wire, thus swinging the counterbalancing weight 40 to one side, as clearly shown in Fig. 4, and the increased weight thus applied to the shorter arm of the coin-balance prevents the coin from moving the longer arm of the balance too far downward.

A single coin-slot 42 is provided in the upper part of the cover of the machine, through which the coins for operating the machine are inserted. As the machine illustrated in the drawings is intended to be operated by five and ten cent pieces, the coin-slot is made just large enough to receive a five-cent piece and to prevent the insertion of any larger coin. The chutes XV, X, and V are all open at one side, as shown, and provided with coin-retaining flanges extending along the tops and bottoms of the chutes. The chute XV has at its open side a lower flange 43, and it also has an upper flange 43^a, the lower edge of which is at such distance above the bottom of the chute that a coin of the diameter of a dime will not be engaged by the flange 43^a, while a coin of larger diameter, such as a penny or a nickel, will be engaged by said flange 43^a and retained within the chute. Upon the interior of the wall of the chute XV and at the upper part thereof is arranged a cam or projection 45, which deflects the upper part of a dime passing down the chute XV and throws it out of said chute into a receiver 44, having flaring sides and forming the upper end of the chute X. This receiver 44 is suitably formed to keep the dime upon its edge and direct it into the lower part of the chute X, which has flanges 46 and 47 for retaining the dime in the chute until it passes from the chute into the primary compartment of the coin-balance. If a dime is inserted in the machine, therefore, it will be thrown out of the chute XV and carried by the chute X to the primary compartment of the coin-balance. The chute V, which is a continuation of the chute XV, has flanges 48 and 49^a, which will retain a five-cent piece. A five-cent piece inserted in the coin-slot will therefore be carried into the secondary pocket of the coin-balance. The first or upper portion 48^a of the flange 48 is low enough to retain a coin of the diameter of a penny; but the remainder of this flange is cut away, as indicated at 48^b, so that the distance between the bottom of the chute and the lower edge of the portion 48^b is less than the diameter of a penny. If a penny is inserted in the machine, it will go down through the chute XV and into the chute V, and it will then be ejected by a cam or projection 49^a, secured to the inner side of the chute V. The penny after leaving the chute V will fall into a trough or chute P and be conducted out of the machine through the opening 50 in the casing. The machine, therefore, cannot be operated by a penny.

The lower ends α and ν of the coin-chutes X and V are inclined laterally in the same direction, as shown, toward the compartments of the coin-balance. When a nickel is inserted in the machine, it will be delivered into the secondary pocket of the coin-balance in the manner described and a single ticket will be delivered. If a dime is inserted, this coin will enter the primary pocket of the coin-balance, and two tickets will be delivered. Pennies inserted in the machine will be thrown into the chute V and carried out of the machine without operating it. In practice after a coin has been inserted in the machine and the motor is in operation another coin may be inserted before the machine comes to a stop. In such case it is necessary to prevent the second coin from interfering with the operation of the machine. For this purpose a coin-chute R is arranged at the right of the chutes X and V and below the laterally-inclined ends α and ν of the same, so that when the coin-balance is tilted into its lower position by the weight of one coin another coin inserted in the machine will pass directly into the chute R and roll downward into the chute P and out through the opening 50.

In Fig. 7 the coin-balance is shown in its normal position, wherein it will be evident that a coin passing through the inclined end ν of the chute V (or the inclined end α of the chute X) will fall into the coin-balance; but when the coin-balance is depressed by the weight of one coin, as indicated diagrammatically in Fig. 8, the coin d will pass over the top of the coin-balance and into the chute R. The coin will therefore pass to the outer side of the machine, so that the customer may regain it.

I claim—

1. In a vending-machine, a motor, a coin-chute, a coin-balance having means connected therewith for stopping and releasing the motor, said balance having primary and secondary coin-compartments, means for retaining a coin in each of said compartments, and means for releasing the coin from said compartments successively.
2. In a vending-machine, a motor, a coin-chute, a coin-balance having means connected therewith for stopping and releasing the motor, said balance having a primary compartment adapted to receive a coin from the chute and a secondary compartment adapted to receive the coin from said primary compartment, coin-retaining devices for each of said compartments and means actuated by the motor for releasing the coin from the primary compartment after a given movement of the motor, and for releasing the coin from said secondary compartment after a further movement of the motor.
3. In a vending-machine, a motor, a coin-balance movable to release and start the mo-

tor, said balance having primary and secondary coin-compartments and a coin-retainer for each compartment, means for directing a coin into said primary compartment, and means, actuated by the motor, for operating the coin-retainers of the primary and secondary compartments successively.

4. In a vending-machine, a motor, a pivoted coin-balance having primary and secondary coin-compartments arranged at successively greater distances from its pivotal point, a coin-retainer for each compartment, means for directing a coin into the primary compartment, and means, actuated by the motor, for operating said coin-retainers.

5. In a vending-machine, the combination with a motor and a coin-balance having means connected therewith for stopping and releasing the motor, said balance having primary and secondary compartments and a coin-retainer for each compartment, of a chute for delivering a coin into the primary compartment, a device movable by the motor, and means actuated by said device for moving said coin-retainers to release the coin from said compartments successively.

6. In a vending-machine, a coin-chute, a motor, a coin-balance having means connected therewith for stopping and releasing the motor, said balance having a primary compartment adapted to receive a coin from the coin-chute and a secondary compartment adapted to receive the coin from the primary compartment, coin-retainers for each of said compartments, said coin-retainers being pivotally connected to the balance and having laterally-projecting arms, a device for engaging and moving said arms, and means actuated by the motor for moving said device.

7. In a vending-machine, a coin-chute, a motor, a coin-balance having means connected therewith for stopping and releasing the motor, said balance having a primary compartment adapted to receive a coin from the coin-chute and a secondary compartment adapted to receive the coin from the primary compartment, coin-retainers for each of said compartments, said coin-retainers being pivotally connected to the balance and having laterally-projecting arms, the forked lever F for engaging and moving said arms, and a cam, actuated by the motor, for moving said forked lever intermittently.

8. In a vending-machine, the pivoted coin-balance having primary and secondary coin-compartments arranged at different distances from the pivotal point of the balance, coin-retainers for said compartments, means for releasing the coin from said compartments successively, and a freely-suspended counterbalance adapted to be engaged by the coin-balance when the latter is tilted by the weight of a coin.

9. In a vending-machine, a coin-chute hav-

ing its lower or discharge end laterally inclined, a coin-balance normally in position to receive a coin from said chute, and a chute at one side of said balance arranged to receive coins from the inclined end of said first-mentioned chute when the coin-balance is moved from its normal position by a coin.

In testimony whereof I affix my signature in presence of two witnesses.

GEORGE C. YOCUM.
